PORTABLE SAUNA BATH

Robert E. Gorton, Hayward, Calif., assignor to Magna
Five, Inc., San Jose, Calif.

Filed Jan. 10, 1966, Ser. No. 549

Term of patent 14 years

(Cl. D83—1)

FIG. 1 is a front-side perspective view of a portable sauna bath, showing my new design therefor.

FIG. 2 is a top plan view of the same.

FIG. 3 is a back elevational view of the same.

FIG. 4 is a side elevation of FIG. 1 as seen from the left hand side therein.

FIG. 5 is a front elevational view; and

FIG. 6 is a side elevation of the right hand side of the portable sauna bath of the present invention.

I claim:

The ornamental design for a portable sauna bath, as shown.
